UNITED STATES PATENT OFFICE.

ELZY R. WILLIAMS, OF ST. JOSEPH, MISSOURI.

TRIGGER MECHANISM.

959,413.

Specification of Letters Patent. Patented May 24, 1910.

Application filed February 2, 1910. Serial No. 541,584.

To all whom it may concern:

Be it known that I, ELZY R. WILLIAMS, a citizen of the United States, and a resident of St. Joseph, in the county of Buchanan and State of Missouri, have invented a new and Improved Trigger Mechanism, of which the following is a full, clear, and exact description.

The invention relates to trigger mechanisms such as shown and described in the Letters Patent of the United States, No. 938,192, granted to me on October 26, 1909.

The object of the present invention is to provide certain new and useful improvements in trigger mechanisms, whereby an auxiliary trigger can be readily set for action whenever it is desired to provide a sensitive action of the trigger mechanism.

For the purpose mentioned, use is made of an abutment mounted to swing on the pivot of the main trigger, to abut against a fixed part of the fire-arm, a spring-pressed manually-controlled mechanism mounted on the main trigger and adapted to engage the said abutment, and an auxiliary trigger fulcrumed on the main trigger and provided with a catch, adapted to engage the said mechanism, to hold the latter under tension and against the said abutment, so that when the auxiliary trigger is pressed the main trigger is released.

A practical embodiment of the invention is represented in the accompanying drawings forming a part of this specification, in which similar characters of reference indicate corresponding parts in all the views.

Figure 1 is a side elevation of the trigger mechanism as applied to a breech-loading fire-arm, the stock of which is shown in section; Figure 2 is an enlarged elevation of the left-hand side of the trigger mechanism and showing the auxiliary trigger out of action; Fig. 3 is an elevation of the right-hand side of the trigger mechanism, parts being in section; Fig. 4 is an elevation of the forward edge of the trigger mechanism; Fig. 5 is a like view of the rear edge of the trigger mechanism; Fig. 6 is an elevation of the left-hand side of the trigger mechanism with the auxiliary trigger set for action and the main trigger in engagement with the hammer; and Fig. 7 is a similar view of the right-hand side of the same.

The fire-arm on which the trigger mechanism is applied, consists of the usual stock A, the barrel B, the hammer C, the spring

C', the main trigger D, mounted to swing on a pivot D' and pressed on by a main trigger spring D², the breech block E and the lever F for operating the breech block 60 E and for forming the trigger guard.

An auxiliary trigger G is arranged on the front of the finger piece of the main trigger D, and is pivoted at G' in a central slot of the said finger piece and pressed on by a 65 spring G², the swinging movement of the auxiliary trigger G being limited by a stop pin G³, as plainly indicated in Fig. 3. A catch G⁴ extends angularly from the pivotal end of the auxiliary trigger G, and is adapted to engage the upper end of a lever H, fulcrumed at its lower end at H' in the slot of the main trigger D, and the said lever H is provided with a spring H² bearing against a pin H³, held on the main trigger D, so as to normally hold the lever H in a rearmost position, as indicated in Fig. 3. On the lever H is secured a handle H⁴, projecting through a slot D³ on the right-hand side of the main trigger D, so that the 80 operator can take hold of the handle H⁴, with a view to swing the lever H forward against the tension of its spring H² and for engagement with the catch G⁴ of the auxiliary trigger G (see Fig. 7). On the lever H, at a point between the pivot H' and the handle H⁴ is secured a pin H⁵, working in the slot D⁴ in the main trigger and engaging the forked end I' of a setting lever I, fulcrumed at I² on the side of the main trigger 90 D. The lower end of the lever I is adapted to engage an angular arm J' formed on the free end of a heavy spring J, secured at its upper end J² to the side of the main trigger D, as plainly indicated in Figs. 2 and 6. The upper pointed end I³ of the lever I is adapted to engage a block K, held on an arm K', fulcrumed at K² on an abutment L, hung loosely on the pivot D' of the main trigger D and extending down on the side 100 of the main trigger on which the setting lever I is pivoted. A spring K² presses the block K, to hold the same normally in a downward position against a stop pin K⁴, carried by the abutment L, so that when the lever H is swung forward by the operator, as previously mentioned, then the pin H⁵ imparts a swinging motion to the lever I, so that the pointed end I³ engages and raises the block K, to finally pass the same, after 105 which the block K is pressed back to its previous position by its spring K², to be finally 110

engaged by the pointed end I^3 of the lever I , as plainly shown in Fig. 6, to hold the setting lever I in a locked position. The abutment L is pressed on by a spring L' , to normally hold the same in a forward position, and on the forward end of the abutment L is secured an adjustable screw pin L^2 , adapted to abut against a shoulder A' formed on the frame, and which shoulder is preferably 10 the forward wall of the slot through which extends the main trigger D .

The operation is as follows: When the several parts are in the position shown in Figs. 1, 2 and 3, then the auxiliary trigger G is out of action and the main trigger D is used in the usual manner, for releasing the hammer C . When it is desired to make use of the auxiliary trigger G , then the operator takes hold of the handle H^4 and 15 pushes the same forward, so as to engage the lever H with the catch G^4 of the auxiliary trigger G , and to impart a swinging motion to the setting lever I , so as to engage the block K thereof and to place the spring J under tension. Now as the spring J bears on the lower end of the lever I , the upper pointed end I^3 thereof presses against the block K , so as to hold the pin L^2 in firm abutment with the shoulder A' of the frame. 20 The hammer C is now cocked in the usual manner, and when the operator slightly presses the auxiliary trigger G in a rearward direction, then its catch G^4 disengages the lever H , thus releasing the same and 25 allowing its spring H^2 to swing the lever H rearward, and also allowing the spring J to press on the lever I , to force the main trigger D in a rearward direction, as the upper end I^3 of the lever I is held against swinging movement by abutting against the block K mounted on the abutment L , abutting with its pin L^2 on the shoulder A' . Thus 30 when the main trigger D is swung rearward as described, it releases the hammer C and the fire-arm is discharged. 35

It is understood that when the lever H is released by the auxiliary trigger G , it swings back to its normal rearward position, as before mentioned, so that after the fire-arm is 40 discharged the several parts are again in normal position with the auxiliary trigger out of action, and whenever it is desired to re-use the auxiliary trigger, it has to be raised by the operator manipulating the handle H^4 , as previously explained.

Having thus described my invention, I claim as new and desire to secure by Letters Patent:

1. A trigger mechanism for fire-arms,

comprising a main trigger, an abutment 60 mounted to swing and adapted to abut against a fixed part of the fire-arm, a spring-pressed manually-controlled mechanism mounted on the said main trigger and adapted to engage the said abutment, and an auxiliary trigger fulcrumed on the said main trigger and provided with a catch adapted to engage the said mechanism to hold the latter under tension and against the said abutment. 70

2. A trigger mechanism for fire-arms, comprising a main trigger, an abutment hung loosely on the pivot of the said main trigger and adapted to abut against a fixed part of the fire-arm, a spring fixed on the 75 said main trigger, a manually-controlled device mounted on the said main trigger and adapted to place the said spring under tension and to abut on the said abutment, and an auxiliary trigger adapted to engage and 80 lock the said mechanism in active position.

3. A trigger mechanism for fire-arms, comprising a main trigger, an abutment mounted to swing on the pivot of the main trigger and adapted to abut against a fixed 85 part of the fire-arm, a spring-pressed block movable on the said abutment, a spring fixed on the said main trigger, a manually controlled lever device mounted on the said main trigger and adapted to place the said spring 90 under tension and to engage the said abutment block, and an auxiliary trigger fulcrumed on the said main trigger and having a catch for engaging the said lever mechanism to lock the same at the time the said 95 spring is under tension.

4. A trigger mechanism for fire-arms, comprising a main trigger, an auxiliary trigger fulcrumed on the said main trigger and having a catch, a spring-pressed lever 100 fulcrumed on the main trigger and adapted to be engaged by the said catch, an abutment lever fulcrumed on the said main trigger and controlled by the said spring-pressed lever, a spring secured on the said main trigger and adapted to be placed under tension 105 by the said abutment lever, and an abutment having a spring-pressed block and adapted to engage a fixed part of the fire-arm, and the said block being adapted to be engaged 110 by the said locking lever.

In testimony whereof I have signed my name to this specification in the presence of two subscribing witnesses.

ELZY R. WILLIAMS.
